ELECTRIC LAMP SOCKET

Filed May 6, 1926

2 Sheets-Sheet 2

UNITED STATES PATENT OFFICE.

WILLIAM ILE, OF JACKSON, MICHIGAN, ASSIGNOR TO REYNOLDS SPRING COMPANY, OF JACKSON, MICHIGAN, A CORPORATION OF DELAWARE.

ELECTRIC-LAMP SOCKET.

Application filed May 6, 1926. Serial No. 107,285.

The invention relates to improvements in electric lamp sockets.

The object of the present invention is to improve the construction of electric lamp sockets and to provide a simple, and comparatively inexpensive construction which will be strong and durable and which will enable the parts to be easily and quickly assembled.

10 A further object of the invention is to provide an electric lamp socket construction in which the parts will be rigidly maintained in position so that there will be no liability in the use of the socket of the parts becoming loose and accidentally short circuiting or otherwise becoming inoperative.

It is also an object of the invention to provide a lamp socket adapted to afford ample air space around the conductor elements so 20 that there will be no liability of arcing or sparking.

Another object of the invention is to interlock the screw shell contacts with the insulating body so that there will be no liability of the screw shells becoming loose and 25 rotating in the insulating body when screwing the plug of an electric lamp into and out of them.

With these and other objects in view, the 30 invention consists in the construction and novel combination and arrangement of parts hereinafter fully described, illustrated in the accompanying drawings and pointed out in the claims hereto appended, it being understood that various changes in the form, proportion and minor details of construction, 35 within the scope of the claims, may be resorted to without departing from the spirit or sacrificing any of the advantages of the 40 invention.

In the drawings:—

Figure 1 is a side elevation of a double lamp socket constructed in accordance with this invention.

45 Fig. 2 is a central longitudinal sectional view.

Fig. 3 is a longitudinal sectional view taken substantially on the line 3—3 of Fig. 2.

50 Fig. 4 is a horizontal sectional view through the upper portion of the device.

Fig. 5 is an elevation of one of the sections of the insulating body showing the inner face thereof.

55 Fig. 6 is a similar view showing the outer face of the section.

Fig. 7 is a detail perspective view of the interior screw shell contacts and the conductor bar thereof.

Fig. 8 is a detail perspective view of the exterior screw shell contact.

Fig. 9 is a detail perspective view of the end section or button of insulating material.

Fig. 10 is a central longitudinal sectional view of a triple socket constructed in accordance with this invention.

Fig. 11 is a side elevation of one of the sections of the insulating body showing the inner face of the section.

Fig. 12 is a similar view illustrating the outer face of the section.

Referring particularly to the double socket illustrated in Figs. 1 to 9 inclusive, the insulating body of the socket is divided longitudinally into two sections 1, each section being molded and consisting of a single piece 75 of Bakelite or similar plastic insulating material and composed of an upper neck 2 and downwardly diverging sockets 3 in which are arranged screw shell contacts 4 constructed of suitable conducting material and secured together at their adjacent sides at 5 by solder or other suitable means located in an opening 6 in the adjacent wall or portion 7 of the downwardly diverging sockets 3. The screw shell contacts are provided at 85 their opposite sides with projecting lugs 8 arranged in recesses 9 in the inner faces of the outer walls of the sockets 3. The lugs 8 and the connecting portions of the screw shell contacts interlock the latter with the 90 insulating body and prevent any rotary movement of the screw shell contacts when screwing the plug of a lamp into and out of the device.

The screw shell contacts are provided in 95 their top walls with openings 10 for the reception of the terminals 11 of a center contact bar 12 arranged in substantially horizontal position and in spaced relation with the shell contacts and fitted in a substantial- 100 ly horizontal groove 13 in each section of the insulating body. The upper neck portion of the insulating body is cylindrical and each section is provided with a central longitudinal semi-cylindrical recess 14 and it 105 has side recesses 15 located at opposite sides of the central recess 14. Each section of the body portion is also provided at the bottom of the recess 14 with substantially horizontal recess 16 and the said horizontal groove is 110

formed in the horizontal recess which provides an air space at the center contact bar 12. A central contact bar 12 is composed of a central horizontal portion and downwardly diverging intermediate portions and terminal contact portions arranged at an obtuse angle to the downwardly diverging intermediate portions and in substantially the plane of the top walls of the interior shell contacts. One of the shell contacts is provided with a conductor bar 17 which is approximately L-shaped and which is arranged in L-shaped grooves 18 formed in the side recesses 15. The side recesses 15 are approximately L-shaped as shown and the grooves 18 which conform generally to the configuration of the recesses are adapted to permit the conductor bar 17 to be arranged at either side of the central longitudinal recess 14. This provides a reversible structure and facilitates a rapid assembling of the parts. The center contact bar is also reversible and may be readily placed in its groove.

The upper neck portion of the insulating body is provided at the bottom thereof with a supporting rib 19 and it has a central exterior recess 20 extending upwardly from the rib at the outer side of each of its sections to receive a tongue 21 of an exterior screw shell contact 22 whereby the latter is interlocked with the neck of the insulating body and held against rotary movement thereon. Each section of the insulating body is preferably reinforced below the neck with a vertical rib 23. The exterior screw shell contact is fitted on the neck and is provided in its top wall with an opening 24 and the tongue 21 which depends from the top of the exterior screw shell contact is formed of a portion of the metal cut from the top wall of the exterior shell to form the top opening 24. The top wall of the exterior screw shell is provided with a depression 25 and the upper terminal 26 of the conductor bar 17 is bent downwardly into the depression of the exterior screw shell contact into electrical engagement with the same.

The opening 24 in the top wall of the exterior screw shell contact receives an enlargement 27 of a button or top section 28 of Bakelite or other suitable insulating material. The enlargement 27 interlocks the button or top section 28 with the exterior screw shell contact and prevents rotary movement of the top section which is provided with a central opening 29 through which passes a screw 30 having a head at its upper end and having a lower threaded end which engages a threaded perforation 31 in the center contact bar. The top section 28 is provided with a metallic bushing 32 flanged at its upper end engaged by the head of the screw which head is preferably polygonal as shown but any other desired construction may of course be employed and forms a central projecting

contact. The upper and lower walls of the central semi-cylindrical recess of each section of the insulating body is provided with a notch or recess 33 to form openings for the passage of the central connecting and conductor screw. The two sections of insulating body are connected by a transverse bolt 34 which pierces the wall 7 between the interior shell contacts. The central longitudinal recess and the side recesses and the bottom recess provide air spaces around the conductor elements to prevent arcing or sparking and the grooves in the recesses and the notches in the top and bottom walls of the central recess hold the conductor elements firmly in position and there is no liability of short circuiting, arcing or sparking.

In Figs. 10 to 12 inclusive is illustrated a triple socket which is constructed substantially the same as the double socket, the insulating body being composed of two sections 35 of Bakelite or similar material and having an upper neck portion 36 and provided with downwardly diverging side sockets 37 and a central downwardly extending vertical socket 38 located between the side sockets 37. The neck portion is provided in each of the sections with a central vertical semi-cylindrical recess 39 and it has side recesses 40 and a bottom substantially horizontal recess 41. The side recesses are approximately L-shaped and are provided with approximately L-shaped grooves 42 and the bottom horizontal recess is provided with a horizontal groove 43. The sockets 37 and 38 receive interior screw shell contacts 44 and 45 which are connected together at their adjacent sides at 46 by solder or other suitable means arranged in openings 47 in the adjacent dividing walls of the sockets and the side shell contacts are provided at their outer sides with projecting lugs 48 which engage recesses 49 in the inner faces of the walls of the side sockets at the outer side thereof. The lugs and the connected portions of the shell contacts prevent rotary movement of the said shell contacts as heretofore described. The horizontal groove 43 receives a center contact bar 50 which has its terminals 51 arranged in openings in the top walls of the side shell contacts and the center conductor and connecting screw 52 engages a threaded opening 53 in the center of the contact bar 50 and projects downwardly therefrom through an opening formed by notches 54 in the bottom wall of the horizontal recess and the lower end of the screw provides a central contact for the central screw shell contact.

One of the side screw shell contacts has mounted on it an approximately L-shaped conductor bar 55 which is fitted in the grooves of the side recesses at one side of the central recess and the said conductor bars is rigidly secured to the shell contact similar

to the conductor bar of the double socket by soldering or other suitable means. The upper end 56 of the conductor bar 55 is bent into engagement with the exterior shell contact 57. The exterior shell contact 57 and the exterior of the neck portion of the sections are constructed exactly as heretofore described in connection with the double socket and the cap 58 is also constructed and arranged exactly the same as the cap of the double socket. As the details of the neck, the exterior screw shell contact and the top section are identically the same as the corresponding parts of the double socket a detailed description of these parts is deemed unnecessary. The parts of the triple socket are reversible and air spaces are provided around the conductor elements. The two sections of the insulating body are secured together by bolts 59 piercing the walls between the sockets in the same manner as the sections of the double insulating body of the double socket.

What I claim is:

1. An electric lamp socket including an insulating body divided longitudinally and composed of two sections and provided with an upper neck portion and having lower sockets, said sections being provided with a central vertical recess and having side recesses located at opposite sides of the central recess and a bottom transversely disposed recess arranged below the central recess and extending to opposite sides thereof, interior screw shell contacts arranged in the said sockets, an exterior shell contact arranged on the neck, a conductor bar arranged in the side recesses of the sections at one side of the central recess and electrically connecting the exterior shell contact with one of the interior shell contacts, a central conducting bar arranged in the bottom recess, the side recesses and the bottom recess permitting a reversal of the parts to enable the same to be quickly assembled, a top insulating section fitted against the exterior screw shell contact and a combined conductor and connecting screw piercing the top section and connected with the center contact bar.
2. An electric lamp socket including an insulating body divided longitudinally and composed of two sections and provided with an upper neck portion and having lower sockets, said sections being provided with a central vertical recess and having side recesses located at opposite sides of the central recess, a bottom recess arranged below the central recess, said sections being also provided in the side recesses and bottom re-
- cesses with grooves, the side grooves being equally spaced from the center and the bottom groove extending to opposite sides of the center of the body, interior shell contacts arranged in the sockets and abutting against the upper ends thereof, an exterior shell contact arranged on the neck portion of the insulating body, a conductor bar fitted in the grooves of the side recesses at one side of the center recess and interlocked with the sections and electrically connecting one of the interior shell contacts with the exterior shell contact, a center contact bar fitted in the bottom grooves and interlocked with the sections of the insulating body the side and bottom grooves permitting a reversal of parts to enable the same to be quickly assembled, a top insulating section fitted against the exterior shell contact and a connecting and conductor screw piercing the top section and having a threaded engagement with the center contact bar.
3. An electric lamp socket including an insulating body divided longitudinally and composed of two sections provided with an upper neck and having a pair of lower diverging sockets and a lower central vertical socket, the inner faces of the sections being provided with central, side and bottom recesses located at opposite sides of the center of the body and the bottom recess extending to opposite sides of the center, interior screw shell contacts arranged within the said sockets and abutting against the upper ends thereof and electrically connected with each other and provided with top openings, an exterior screw shell contact arranged on the neck of the insulating body, a conductor bar arranged in the side recesses at one side of the central recess and electrically connecting the exterior shell contact with one of the interior shell contacts, the central and side recesses permitting a reversal of parts to enable the same to be quickly assembled, a center contact bar mounted in the bottom recesses of the sections and having its terminals arranged in the openings of the shell contacts of the diverging sockets, a top insulating section fitted on the exterior shell contact and a combined conductor and connecting screw piercing the top section and having a threaded connection with the central contact bar and projecting therefrom and forming a center contact at the opening of the shell of the vertical socket.

In testimony whereof I have hereunto set my hand.

WILLIAM ILE.
